UNITED STATES PATENT OFFICE

113,755

DESIGN FOR A COMBINED BACK GUARD AND HIGH CLOSET FOR RANGES

John R. Morgan, Oak Park, Ill., assignor to Sears, Roebuck and Co., Chicago, Ill., a corporation of New York

Application October 8, 1938, Serial No. 80,327

Term of patent 7 years

To all whom it may concern:

Be it known that I, John R. Morgan, a citizen of the Republic of Guatemala, residing in Oak Park, in the county of Cook and State of Illinois, have invented a new, original, and ornamental Design for a Combined Back Guard and High Closet for Ranges, of which the following is a specification, reference being had to the accompanying drawing, forming a part thereof.

The drawing is a perspective view of a combined

back guard and high closet for ranges embodying
my new design.

The side not shown is substantially similar to the side which is shown.

I claim:

The ornamental design for a combined back guard and high closet for ranges, as shown and described.

JOHN R. MORGAN.
